UNITED STATES PATENT OFFICE.

WILLIAM KIECKHEFER, OF MILWAUKEE, WISCONSIN.

BOOKMARK.

1,420,265.

Specification of Letters Patent. Patented June 20, 1922.

Application filed October 12, 1921. Serial No. 507,175.

To all whom it may concern:

Be it known that I, WILLIAM KIECKHEFER, a citizen of the United States, residing at Milwaukee, in the county of Milwaukee and 5 State of Wisconsin, have invented certain new and useful Improvements in Bookmarks, of which the following is a specification.

This invention relates to book marks and 10 the primary object of the present invention is to provide a novel book mark of simple and durable construction having means for indicating not only the particular page of a book, but also a particular column and 15 paragraph on the said page.

A further object of the said invention is 20 the provision of a novel book mark embodying a sheath for the reception of a pair of indicating slides, said slides having suitable indicia thereon to indicate the particular column and paragraph of a page of a book with which the mark is associated, the sheath having means formed thereon for preventing 25 relative movement thereof in relation to the book, whereby the indicating slides may be held beyond the outer edge of the book so that the same can be readily seen by the user of the book.

A still further object of the invention is 30 to provide a novel means for associating the indicating slides with the sheath and a novel means formed on said indicating slides so as to allow the ready operation thereof and so as to insure against the 35 accidental movement thereof in said sheath after the actuation of the slides.

With these and other objects in view, the invention consists in the novel construction, arrangement and formation of parts, as will 40 be hereinafter more fully described, claimed and illustrated in the accompanying drawings, forming a part of this specification, in which drawings:

Figure 1 is a perspective view of the improved book mark in use.

Figure 2 is an elevation of the improved book mark.

Figure 3 is a longitudinal section through the book mark, taken on the line 3—3 of 50 Figure 2.

Figure 4 is a transverse section through the mark taken on the line 4—4 of Figure 2.

Figure 5 is detail enlarged perspective view of one end of the sheath or casing 55 forming a part of the mark.

Figure 6 is an elevation of one of the slides which is to be associated with the sheath or casing, and

Figure 7 is an elevation of the other slide which is to be also associated with the 60 sheath or casing.

Referring to the drawings in detail, wherein similar reference characters designate corresponding parts throughout the several views, the reference character 10 indicates the novel book mark and 15 a book, with which it can be associated.

The book 15, is of course, of any size or shape, and has the pages 16 thereof each divided into columns 17 and 18. It is to be 70 understood, of course, that the mark is to be used also in connection with books in which the pages are not divided into columns.

The improved mark 10 comprises the 75 sheath or casing 20 and the slides 25 and 30.

The sheath or casing 20 as well as the slides 25 and 30 are adapted to be formed from relatively thin material, such as celluloid or the like, so that the whole mark will 80 be of a relatively thin nature to prevent straining of the back of the book and to prevent any bulge in the book when the mark is placed therein.

The sheath or casing 20 is of elongated 85 form and includes the front and rear walls 21 and 22 and the longitudinally extending side walls 23. The rear wall 22 may be provided at one end or at both ends with inwardly extending right angularly disposed 90 feet 24, which are adapted to engage the side edges of the book to prevent relative longitudinal movement of the mark in relation to a book leaf or page. The space between the front and rear walls 21 and 22 95 is just sufficient to receive the slides 25 and 30, and it is preferred that the slides 25 and 30 be in frictional contact with each other and with the front and rear walls 21 and 22 of the case or sheath 20.

The front and rear walls 21 and 22 intermediate their ends are provided with openings or slots 26, so that the slides 25 and 30 can be readily engaged in order to permit the sliding thereof within the sheath 105 or case 20.

The slides 25 and 30 are each formed identically the same in shape and each includes the longitudinally extending relatively thin body having one face thereof 110

provided with transversely extending corrugations or serrations 27. The smooth faces of the slides 25 and 30 are adapted to be placed together, so that the serrations 5 or corrugations thereon will lie directly in rear of the slots or openings 26, where the same can be readily engaged by the user of the mark, in order to facilitate the sliding of the slides within the case or sheath 20. 10 It also can be seen that the corrugations 27 form means for engaging the case or sheath 20 in order to prevent accidental sliding of the slides within the casing or sheath.

Each of the slides 25 and 30 have printed 15 thereon at each end thereof suitable indicia in order to indicate the page or column and the paragraph in the page or column to which the user's attention is to be attracted at a later time. The slide 25 has written or 20 printed thereon at one end, the capital "A" as at 28, while its opposite end has printed or otherwise placed thereon the capital "B" as at 29. Adjacent to the "A" and "B" are placed small letters "A", "B", "C", and "D", 25 as at 28'.

The slide 30 has placed thereon in any preferred manner at one end the capital "C" as indicated by the numeral 31 and has the letter "D" on its opposite end, as at 32 and 30 adjacent to the letters "C" and "D" are placed relatively small letters "A", "B", "C", and "D", indicated by the numeral 33.

The large letters "A", "B", "C" and "D" are adapted to indicate the page or column 35 where the user left off or to a certain passage where the user desires his attention to be called at a later time, while the small letters "A", "B", "C", "D" on each of the slides indicate the paragraph or portions of 40 the page or column nearest the point where the user of the book left off.

In use of the mark, the same is placed between the leaves of the book where the reader thereof left off, and if the book is of the type 45 having only one column on each page, and the reader left off on the left hand page, the slide 25 would be pushed out until the large letter "A" indicated by the numeral 28 appears; the letter "A" indicating the first or 50 left hand page. Now, if the reader left off on the right hand page, the slide would be pushed out until the large letter "B" indicated by the numeral 29 appears, the letter "B" indicating the second or the right hand 55 page. Now, if the reader left off at the first paragraph, the slide would be actuated until the small letter "A" appears, and if he left off at the second paragraph the slide would be actuated until the small letter "B" appears. 60 If he left off at the third paragraph the slide would be actuated until the small letter "D" appeared, etc. If the page is not divided off into paragraphs, the small letter "A" would

indicate that he left off at the extreme upper end of the page, the small letters "B" and 65 "C" would indicate that he left off at an intermediate portion of the page and the small letter "D" at the extreme lower end of the page. If the mark is used with the type of book having two columns on each page both 70 of the slides are used, and the large letters "A", "B", "C" and "D" would each indicate one of the columns instead of a page. The small letters "A", "B", "C" and "D" would be used in the same manner as heretofore described. 75

From the foregoing description, it can be seen that a novel and simple book mark has been provided, which will effectively indicate the page, column and paragraph where 80 the reader of the book left off.

Changes in details may be made without departing from the spirit or scope of this invention; but,

I claim:

1. A book mark comprising a longitudinally extending sheath, slide plates slidably mounted within said sheath, means on said slides for facilitating the sliding thereof in said sheath, and indicia disposed on said slides for indicating the column or page and paragraph of a particular portion of a book. 90

2. A book mark comprising a longitudinally extending hollow sheath, a plate slidably mounted in said sheath, indicia carried by the opposite ends of the plate for indicating the page, column and certain portion of a page of a particular part of a book, the indicia being disposed so that only certain portions thereof will be exposed as the plate 100 is moved outwardly of the sheath.

3. A book mark comprising a longitudinally extending hollow sheath having front and rear walls provided with actuating openings, a plate slidably mounted in said sheath 105 having corrugations formed thereon adapted to appear in rear of said actuating openings, and indicia carried by the terminals of the plate.

4. A book mark comprising a longitudinally extending hollow sheath having front and rear walls provided with actuating openings, a pair of plates slidably mounted within the sheath having the outer faces thereof provided with corrugations adapted to appear in rear of said openings and adapted to frictionally engage the inner surface of the front and rear walls of the sheath, and indicia carried by the terminals of the plates. 110

5. A book mark comprising a hollow 120 sheath, slide plates mounted in the sheath, indicia on said slide plates and a right angularly extending foot formed on the sheath for limiting the movement of a sheath in a book in one direction.

WILLIAM KIECKHEFER.
